Primary Examiner — John Windmuller*Assistant Examiner* — Steven J Czyz(74) *Attorney, Agent, or Firm* — Woodard, Emhardt,
Moriarty, McNett & Henry LLP(57) **CLAIM**

The ornamental design for a medications dispensing apparatus, as shown and described.

DESCRIPTION

FIG. 1 is a top perspective view of a medications dispensing apparatus;

FIG. 2 is a bottom perspective view thereof;

FIG. 3 is a rotated perspective view thereof;

FIG. 4 is a front elevational view thereof;

FIG. 5 is a back elevational view thereof;

FIG. 6 is a left elevational view thereof;

FIG. 7 is a right elevational view thereof;

FIG. 8 is a top plan view thereof; and,

FIG. 9 is a bottom plan view thereof.

The broken lines depict portions of the article that form no part of the claimed design.

1 Claim, 7 Drawing Sheets(56)
